UNITED STATES PATENT OFFICE.

ANDREAS RADOVANOVIC, OF ZURICH, SWITZERLAND.

COMBUSTION-ENGINE.

1,181,798.

Specification of Letters Patent.

Patented May 2, 1916.

Application filed December 16, 1914. Serial No. 877,560.

To all whom it may concern:

Be it known that I, ANDREAS RADOVANOVIC, a citizen of the Republic of Switzerland, residing at Zurich, Switzerland, have invented 5 new and useful Improvements in Combustion-Engines; and I do hereby declare the following to be a full, clear, and exact description of the invention, such as will enable others skilled in the art to which it 10 appertains to make and use the same, reference being had to the accompanying drawing, and to letters or figures of reference marked thereon, which form a part of this specification.

15 This invention relates to improvements in combustion engines with controlling piston and scavenging of the working cylinder across the axle of the cylinder.

The invention consists in the feature, that 20 for the purpose to obtain a more rapid exhausting of the burned gases, additional exhaust openings are provided in the cylinder opposite the usual exhaust openings, which discharge into a chamber in connection with 25 the exhaust channel, and that between this chamber and the scavenging air channel on the one side and the exhaust channel on the other side controlled shutting-off means are arranged.

30 In the combustion engines hitherto known with scavenging of the working cylinder across the axle of the cylinder the exhaust openings are arranged only on the one half of the circumference of the cylinder. By 35 the addition of a further row of exhaust openings opposite the usual exhaust openings (and above the openings for the entrance of the scavenging air) the cross-section of the exhaust openings is doubled in 40 the beginning of the exhaust; consequently the fall of pressure to atmospheric pressure in the present structure takes place in one-half the time that it does in structures provided with one row of exhaust openings.

45 In the accompanying drawing two forms of execution of the object of the invention are shown by way of example.

Figure 1 is a vertical section through the cylinder of a combustion engine in a first 50 form of execution, Figs. 2 and 3 are horizontal sections through the cylinder on the lines A—B and C—D respectively of Fig. 1, and Fig. 4 a view of the whole engine on a reduced scale; Fig. 5 shows in a horizontal 55 section through the cylinder a further form

of execution of a part of the object of the invention.

In the Figs. 1 to 4 of the drawing z denotes the working cylinder of the combustion engine and k denotes the piston thereof; 60 f are the openings in the cylinder jacket for the entrance of scavenging air in the cylinder and f^1 is the scavenging air channel, a are the usual exhaust openings arranged in the cylinder jacket opposite the 65 openings f and a^1 are the additional exhaust openings, which are arranged in the cylinder opposite the openings a and above the openings f and discharge into the chamber r situated on the outside of the cylinder. 70

a^2 denotes the exhaust channel, in which the exhaust openings a and the chamber r discharge; v is a valve which serves to shut-off the chamber r toward the scavenging air channel f^1 . This valve is controlled by a 75 lever v^1 , v^2 and a cam disk w^1 fixed on a shaft w , which latter is driven by a crank shaft b of the engine by means of a controlling shaft c and bevel gears d (Fig. 4). p denotes throttle valves arranged between the 80 exhaust channel a^2 and the chamber r , i. e. at the places where these rooms run into each other. Each of these valves is controlled by means of a lever p^1 , a rod p^2 , a lever p^3 and a common lever p^4 by the cam disk w^1 85 fixed on the shaft w .

The working of the engine is the following: During its forward stroke the piston k opens the openings a and a^1 , so that the burned gases can stream out through the 90 openings a directly into the exhaust channel a^2 in the direction of the arrows n and through the openings a^1 into the chamber r in the direction of the arrows m ; the throttle valves p being in the open position 95 (drawn in full lines) the burned gases escape from the chamber r into the exhaust channel a^2 (Fig. 2). It is clear that by exhausting through the openings a and the additional openings a^1 the exhaust takes place 100 much quicker, than by exhausting through the exhaust openings a alone. By its further forward stroke the piston k opens the openings f for the scavenging air, which now enters into the cylinder z to expel the 105 exhaust gases in a known manner. At the same time the throttle valves p are closed (as indicated in dotted lines) and the valve v is opened. The scavenging air now flows into the chamber r and from here through 110

the openings a^1 in the cylinder z in the direction of the arrows l . During its return stroke the piston k first closes the openings f , but while the throttle valves are still closed and the valve v is still open, the scavenging air is always streaming into the cylinder till the openings a and a^1 are closed by the piston. By the addition of the openings a^1 not only the exhaust is accelerated, but also the duration of the scavenging is extended, from the moment the piston closes the openings f to the moment it completes the closing of the openings a and a^1 .

Instead of the throttle valves p and the valve v any other throttle- or shut-off means can be provided. An example of such a further form of execution of the object of the invention modified with regard to the throttle means is illustrated in Fig. 5. Instead of the throttle valves p vertical slots s are provided in the outer walls of the chamber r that is at the places where this chamber runs into the exhaust channel a^2 . Through-out these slots air with a higher pressure than that of the scavenging air is blown-in in the direction toward the middle of the cylinder in such a manner that at each side an air wall is formed serving as throttle means, which prevent a directly entering of the scavenging air from the chamber r into the exhaust channel a^2 . For the rest the working of the engine is the same as in the first described example of execution.

The air with a higher pressure than the scavenging air is supplied through a pipe s^2 provided with a shut-off valve s^1 ; the operation of these valves and of the valve v is the same as the operation of the throttle valves p and the valve v in the first described example of execution of the engine.

What I wish to claim is:

1. In a combustion engine, a cylinder having a plurality of exhaust ports in its wall, an exhaust channel into which said ports discharge, a piston in the cylinder controlling the ports, additional exhaust ports diametrically opposite the latter and communicating with the exhaust channel, and means opposite the exhaust ports to inject scavenging air into the cylinder transversely to the axis thereof.

2. In a combustion engine, a cylinder having a plurality of exhaust ports in its wall, an exhaust channel into which the ports discharge, a piston in the cylinder controlling said ports, additional exhaust ports lying opposite the latter and discharging into a chamber in connection with the exhaust channel, and means for injecting scavenging air into the cylinder through said additional exhaust ports.

3. In a combustion engine, a cylinder having a plurality of exhaust ports in its wall, an exhaust channel into which the ports dis-

charge, a piston in the cylinder controlling said ports, additional exhaust ports lying opposite the latter and discharging into a chamber in connection with the exhaust channel, means for scavenging the cylinder, and means to disconnect said chamber and the exhaust channel.

4. In a combustion engine, a cylinder having a plurality of exhaust openings in its wall, an exhaust channel into which said openings discharge, a piston in the cylinder controlling the exhaust openings, additional exhaust openings lying opposite the first mentioned exhaust openings and discharging into a chamber in connection with the exhaust channel, openings arranged below the said additional exhaust openings and communicating with a channel for supplying scavenging air, means to shut-off the chamber into which the additional exhaust openings discharge, after covering the scavenging openings by the piston, and means to blow scavenging air into the cylinder throughout the said chamber and the additional exhaust openings.

5. In a combustion engine, a cylinder having a plurality of exhaust openings in its wall, an exhaust channel into which said openings discharge, a piston in the cylinder controlling the exhaust openings, additional exhaust openings opposite the latter and discharging into a chamber in connection with the exhaust channel, openings arranged below the said additional exhaust openings and communicating with a channel for supplying scavenging air, means to shut-off the chamber, into which the additional exhaust openings discharge, after covering the scavenging air openings by the piston, a shut off valve between the said chamber and the scavenging air supply channel to blow the scavenging air into the cylinder throughout the additional exhaust openings.

6. In a combustion engine, a cylinder having a plurality of exhaust openings in its wall, an exhaust channel into which these openings discharge, a piston in the cylinder controlling the exhaust openings, additional exhaust openings lying opposite the latter and discharging in a chamber in connection with the exhaust channel, openings arranged below the said additional exhaust openings and communicating with a channel for supplying scavenging air, means to blow air of a higher pressure than that of the scavenging air to shut off the chamber into which the additional exhaust openings discharge toward the exhaust channel after covering the scavenging air openings by the piston, and means to blow scavenging air into the cylinder throughout the said chamber and the additional exhaust openings.

7. In a combustion engine, a cylinder having a plurality of exhaust openings in its wall, an exhaust channel into which said

openings discharge, a piston in the cylinder controlling the exhaust openings, additional exhaust openings lying opposite the latter and discharging into a chamber in connection with the exhaust channel, openings arranged below the said additional exhaust openings and communicating with a channel for supplying scavenging air, openings provided in the wall of the said chamber 5 at the place where this chamber runs into the exhaust channel for discharging air of a higher pressure than that of the scavenging air to shut off said chamber by the

blown-in compressed air toward the exhaust channel after covering the scavenging air 15 openings by the piston, and means to blow scavenging air into the cylinder throughout the said chamber and the additional exhaust openings.

In testimony that I claim the foregoing 20 as my invention, I have signed my name in presence of two subscribing witnesses.

ANDREAS RADOVANOVIC.
